United States Patent Office

Des. 192,294
Patented Feb. 27, 1962

192,294

STILT

John W. Klages, 2630 Sherwood Road, Columbus, Ohio

Filed Dec. 29, 1960, Ser. No. 63,390

Term of patent 14 years

(Cl. D34—5)

FIG. 1

FIG. 3

FIG. 1 is a side elevational view of a stilt showing my new design;

FIG. 2 is a front elevational view thereof; and

FIG. 3 is an enlarged fragmentary perspective view thereof.

I claim:

The ornamental design for a stilt, substantially as shown.
